(57) **CLAIM**

The ornamental design for a front combination lamp for an automobile, as shown and described.

DESCRIPTION

FIG. 1 is a front perspective view of a front combination lamp for an automobile.

FIG. 2 is a front view of a front combination lamp for an automobile.

FIG. 3 is a right side view of a front combination lamp for an automobile; and,

FIG. 4 is a top plan view of a front combination lamp for an automobile.

The broken lines in the drawings illustrate portions of the front combination lamp for an automobile that form no part of the claimed design.
